J. L. DICKINSON, OF DUBUQUE, IOWA.

Letters Patent No. 68,492, dated September 3, 1867.

IMPROVEMENT IN VARIABLE CUT-OFF VALVE-GEAR.

The Schedule referred to in these Letters Patent and making part of the same.

TO ALL WHOM IT MAY CONCERN:

Be it known that I, J. L. DICKINSON, of Dubuque, in the county of Dubuque, and State of Iowa, have invented a new and useful Improvement in Variable Cut-Off; and I do hereby declare that the following is a full, clear, and exact description thereof, which will enable those skilled in the art to make and use the same, reference being had to the accompanying drawings, forming part of this specification.

This invention relates to the manner in which the steam is admitted to the steam-chest of a steam engine, whereby the quantity used is made variable, so as to conform to the power required of the engine; and it consists in attaching to the rod or stem of the oscillating valve an arm, which is operated by two eccentric-rods having different motions, which are connected with the arm by means of a slide, the position of which slide on the arm is controlled by the governor, thereby cutting off the steam at an earlier or later point, also decreasing or increasing the throw of the cut-off valve.

It also consists in an automatic device for detaching the governor, and thereby closing the valve and stopping the engine in case of accident, as will be hereinafter more fully described.

Figure 1 is a side view of the arm with the slide attached.

Figure 2 is an edge view of the same.

Figure 3 is a reverse side view of fig. 1.

Figure 4 is a cross-section through $x-x$ of fig. 3.

Figure 5 is a side view of the sliding plate, to which the wrist of the governor-rod is attached, and which wrist is made detachable for certain purposes.

Figure 6 shows a top view of the wrist detached from the plate.

The position of the cut-off valve, in connection with the steam-chest and main valve of the engine, is shown in red lines in the drawing.

Similar letters of reference indicate corresponding parts.

A represents the stem of the oscillating cut-off valve. B is the arm which is attached to this stem. C represents a sliding block on the arm B, made in two parts. D is a bar, which is vibrated on its centre by the

represents a sliding block on the bar D. This bar D is supported and held in its place by the arm G, which is attached to the eccentric-rods E and F. This bar D is supported and held in its place by the arm G, which is attached to the valve stem, and through which the pivot passes upon which the bar vibrates. The edges of the bar D are bevelled, and the block C is attached to it by cleats a a , which fit the bevelled edges, so that the connection is in the form of a dove-tail, which allows the block a free sliding movement on the bar, while, at the same time, it slides on the arm B. The governor is connected with the block C by the sliding-plate H, a detailed view of which is seen in fig. 5. This plate is adjustable in the block through the slot a' , and is fastened in place by the screw and nut b . This sliding-plate is made in two pieces, the wrist-pin to which the governor-rod is attached being on the upper part, but the two parts are held together by a hook, c , and pin, d . Fig. 6 is a top view of this sliding-plate, showing the way in which the two parts are connected together. e is the wrist-pin, to which the governor-rod is attached. When the engine is running, and the cut-off valve in operation, the two parts of the plate H would appear as seen in fig. 3. f is a spring, which is attached to the wrist-pin e , and which bears against hook c to keep it in place. g is a button, which is attached to the edge of the arm B.

This arrangement is made for the purpose of detaching the governor-rod or severing the connection between the governor and the slide C, and closing the valve in case the governor-belt of the engine should break. In such a case, the slide C would be drawn up by the governor so far on the arm B that the inclined projecting end of the hook would strike the button *g*, and the hook would be forced from the pin *d*, when the two parts of the plate H would be instantly separated, and the slide would drop down till it struck the stop-pin *h*, which would entirely shut off the steam and stop the engine.

As before stated, the bar D is oscillated by the eccentric-rods E and F, and in this connection it should be stated that the slide C is formed of two parts, which, as seen in fig. 4, may be marked 1 and 2. *i* is a disk, which is surrounded by the part 2, although it is attached to the part 1 by the screws *o o*. The bevelled or dove-tailed connection between *i* and the part 2 allows the latter a rotating motion, so that the part 2 (which shows as C in fig. 1) can adjust itself to suit the action of the eccentric-rods.

The rod F may receive its motion directly from an eccentric, or in any other suitable manner, but it is set

or placed in such a position that its motion will be somewhat (say one-eighth) in advance of the other rod, so that, as the governor moves the sliding-block C from the upper rod towards the lower one, the arm B will partake of the earlier (or advance) motion and diminished throw, thereby closing the valve at an earlier point of the stroke; and as the sliding-block is raised towards the upper rod, the arm B receives a later motion and increased throw, thereby admitting steam to the cylinder for a longer portion of the stroke.

It will thus be seen that the increased or diminished throw of the valve, produced by the action of the governor, is combined with the variable action of the eccentrics, whereby the valve is rendered much more sensitive to variations of speed, and the engine given a uniform motion.

I do not confine myself to this particular arrangement as regards the actions of the eccentrics or their effect upon the oscillating valve, as I am aware that this motion and effect may be produced by other means than employing the bar D.

But having thus described my invention, I claim as new, and desire to secure by Letters Patent—

1. In combination with the sliding-block C, formed of the parts 1 and 2, and actuated by the governor, substantially as shown and described, I claim the eccentric-rods E and F, acting upon the bar D or its equivalent and upon the oscillating valve, thereby imparting to the arm the motion of either eccentric-rod, as the speed of the engine requires, substantially as shown and described.
2. The arm G and bar D, in combination with the valve-stem A, to support and maintain eccentric-rods E and F at a uniform distance from the valve-stem or its equivalent, substantially as described.
3. I claim the two eccentric-rods, E and F, arranged with reference to the governor and arm G, for the purposes herein set forth.

J. L. DICKINSON.
